LOUIS C. BROSEMER, OF SACRAMENTO, CALIFORNIA

AMBULANT DISCHARGE DEVICE

Application filed May 28, 1929. Serial No. 366,694.

The invention relates to ambulant discharge devices and particularly the type employed in road oil distributors, said oil distributor being used for spraying road oil, hot asphalt or any bituminous materials used in the construction and maintenance of roads and streets.

The primary object of this invention is to provide a machine of the above mentioned character, adapted to regulate the flow of oil, water or other liquid from the spray pipes of the machine.

A further object of this invention is to provide an ambulant spray machine adapted to be used in a more economical manner than has heretofore been done.

A still further object of this invention is to provide an ambulant discharge device, adapted to be used for either heavy or light liquids without materially altering the construction or arrangements of parts.

A still further object of this invention is to provide means for oscillating the spray pipe so that the angle of the flow of liquid therefrom in respect to the road, may be varied in accordance with the desire of the operator.

Other objects and advantages of this invention will be apparent during the course of the following description.

In the drawings forming a part of this specification and in which like numerals are employed to designate like parts throughout the same.

Figure 1 is a side elevation of the discharge device embodying this invention;

Figure 2 is an end elevation of the spraying device showing the arrangement of the spray pipes;

Figure 3 is a fragmentary cross-sectional view showing the manner in which the joint for each spray nozzle is assembled; and

Figure 4 is an end elevation showing the manner in which the connected spray devices are associated with the water feed pipe.

In the drawings wherein for the purpose of illustration is shown a preferred embodiment of the invention, the numeral 5, generally indicates a wheeled chassis frame mounted upon wheels 6, the rear of which is only shown for the purpose of illustrating

the carriage for the spray device. As is generally the practice common to ambulant spray devices of this nature, a tank 8 may be secured to the chassis frame 5 in a well known manner, by the metal straps 9.

Secured to the chassis frame and in close proximity to the rear end of the liquid tank 8 is a pair of T-joints 10, secured in position by a pair of clamps 11, to the flange portion of the chassis frame 5.

The pipes 12 are connected to the liquid tank 8 for feeding water to a transverse pipe 13, which is journaled in the base portions of the T-joints 10 and is held against lateral displacement by nuts 14, threaded on opposite sides of the pipe 13 and having their inner faces in engagement with the T-joints 10.

The opposite end portions of the pipe 13 are bent at 15 to form parallel extension pipes 16 having their ends threaded in a pair of T-joints 17, provided with a clamping member 18 including means for adjustably holding a spray pipe 19 which will be described in a following paragraph.

The spray pipe 19 may be adjustably mounted in the T-joints 17 for facilitating rotary movement of the spray pipe 19 for necessary adjustments. Openings 20 are provided in the spray pipe 19 for registry with the openings in the T-joints 17, also formed on the spray pipe 19 are a series of spaced projections 21, the end projections extending through opening 22 in the base portion of T-joint 17.

A series of sprinkler nozzles 23 have their inlets 24 screw threaded in the extensions 21 which are also provided with corresponding screw threads 25. Each sprinkler nozzle 23 includes a valve and valve chamber, said valve having its stem 25, secured to crank arms 26 having an angle extension 27 for engagement by suitable operating mechanism such as the cross bar 28 pivotally secured to links 29 that are loosely pivoted on the valve stems 25 and a series of pins 30 for engaging the crank arms 26, by shifting the cross bar 28 laterally causing the pins 30 to engage the crank arms 26, thereby rotating the valve stems for opening and closing the valves 23.

Suitable operating mechanism is provided

for shifting the cross bar 28 laterally including a bracket 33 having a clamping portion 34 adapted to be clamped upon the sprinkler pipe 19. An operating handle 35 is pivoted at 36 to the bracket 33 and the extension 38 of the operating handle 35 is connected to the cross bar 28 by a suitable linkage arrangement 39. The link 39 is connected to an extension 40. It will readily be observed that by imparting motion to the handle 35 carried by the bracket 33, that the cross bar 28 will be caused to move laterally, thereby operating the crank arms 26 which control the liquid flow through the sprinkler nozzles 23.

15 The same mechanism for opening and closing the valves 23 may be employed for rotating the sprinkler pipe 19, thereby increasing or decreasing the opening 20 which is in alignment with the adjustable pipes 16. The 20 angularity of the valves 23 is also adjusted simultaneously. The operating means includes the handle 35 securely held by the pipe 19 by the bracket 33 and the clamp 34 which passes around the sprinkler pipe 19. By 25 moving the handle 35 longitudinally, in respect to the machine frame, the spray pipe 19 may be caused to rotate for accomplishing the objects above mentioned.

Figures 3 and 4 clearly show the invention including the T-joint 17, for rotatably carrying the spray pipe 19. It will be readily observed that the operating handle 35 performs two distinct operations and that compact apparatus has been provided for accomplishing the results.

Attention is directed to Figures 1 and 2 wherein is shown elevating mechanism for raising and lowering the sprinkler pipe 19 for varying conditions. At the rear of the 40 chassis frame 5 is positioned a rotary shaft 41 journaled in the upper edges of the chassis frame by any suitable means such as a shackle bearing or the like. The opposite ends of the rotary shaft 41 are provided with 45 winding drum 42 secured thereon in a rigid manner by keys or gib. Also keyed on the shaft 41 is a gear 43 which extends over the chassis frame and meshes with a worm gear 44 carried by a shaft 45 journaled in a pair 50 of bearings 46 secured to the chassis frame 5 by bolts or welding. The shaft 45 is provided with a crank arm 47 for causing rotation of the drums 42. Wire rope 48 is secured to the drums 42 and to the sprinkler 55 pipe 19, so that by operating the crank 47, the drums will cause the wire ropes 48 to raise or lower the sprinkler pipe 19, relative to the road bed which is being operated upon.

An operator's platform 50 may be secured 60 to the chassis frame 5 by rearwardly extending brackets 51 having angle portions 52 and 53 secured to the platform 50 and chassis frame 5 respectively.

A conventional form of spray orifice 60 65 may be used associated with the spray noz-

zles 23. As shown in the drawings, the spray nozzle 23 is provided with spray orifice members 60 screw threaded in the spray nozzle 23.

It is to be understood that the form of my 70 invention herewith shown and described is to be taken as a preferred example of the same, and that various changes in the shape, size and arrangement of parts may be resorted to without departing from the spirit 75 75 of my invention or the scope of the subjoined claims.

What I claim as new is:—

1. Discharge apparatus of the character 80 described, comprising a supply tank, a discharge pipe in valved communication with the tank, and being rotatably supported to control the valve communication, discharge nozzles carried by the pipe, a valve in each nozzle, and a single means for rotating the 85 pipe and nozzle valves for controlling flow into the pipe and through the nozzles.

2. Discharge apparatus of the character 90 described, comprising a supply tank, a discharge pipe in valved communication with the tank, and being rotatably supported to control the valve communication, discharge nozzles carried by the pipe, a valve in each nozzle, a single means for rotating the pipe 95 and nozzle valves for controlling flow into the pipe and through the nozzles, and said means being shifted in different directions for the operation of the pipe and nozzles.

3. Discharge apparatus of the character 100 described, comprising a supply tank, a discharge pipe in valved communication with the supply tank, and being rotatably supported to control the valve communication, discharge nozzles carried by the pipe, a valve in each nozzle, an arm carried by each nozzle 105 valve, a shiftable bar having pins extending therefrom for operation of the arms, pivotal bracket supports for the bar, and means associated with the bar and pipe for either shifting the bar to operate the nozzle valves 110 or rotating the pipe to control the valve communication.

4. In apparatus of the character described, a journaled pipe having a valved inlet controlled by rotation of the pipe, nozzles carried 115 by the pipe having control valves and a unitary means operable for either rotating the pipe or operating the nozzle valves.

5. In apparatus of the character described, a journaled pipe having a valved inlet controlled by rotation of the pipe, nozzles carried by the pipe having control valves and a unitary means operable for either rotating the pipe or operating the nozzle valves including a lever movable in directions at relative angles to effect said operations.

In testimony whereof, I affix my signature.
LOUIS C. BROSEMER.
